UNITED STATES PATENT OFFICE.

EDGAR L. SWINDLER, OF PALESTINE, TEXAS.

LOCK-JOINT RAIL.

1,093,243.

Specification of Letters Patent.

Patented May 5, 1914.

Application filed September 2, 1913. Serial No. 787,819.

To all whom it may concern:

Be it known that I, EDGAR L. SWINDLER, a citizen of the United States, residing at Palestine, in the county of Anderson and State of Texas, have invented certain new and useful Improvements in Lock-Joint Rails, of which the following is a specification.

This invention relates to new and useful improvements in lock joint rail and has more particular relation to a device for securing together the rails forming a railway track.

The object of the invention is to provide a firm and solid joint connecting railroad rails, which will not be weakened or broken by reason of the passage of cars thereover.

A further object of the invention is to provide a smooth joint which will eliminate the knocking of the car wheels passing over the joint.

A further feature of the invention resides in the simplicity of construction whereby the adjacent ends of the rails may be easily connected or taken apart.

A still further feature of the invention resides in the provision of a modified form of joint whereby a broken rail may be readily replaced in the track without taking up the adjacent rails.

With the above and other objects in view, the invention has particular relation to certain novel features of construction and arrangement of parts, an example of which is given in this specification and illustrated in the accompanying drawings, wherein—

Figure 1 is a plan view of the rail joint connecting the adjacent ends of two contiguous rails. Fig. 2 is a side view thereof. Fig. 3 shows the adjacent ends of two connecting rails, with the splice removed. Fig. 4 shows a side elevation of the splice in reversed position relative to the rails, as shown in Fig. 3. Fig. 5 shows a sectional end view of the ordinary form of rail. Fig. 6 shows a sectional end view of my improved form of connection, taken through the splice. Fig. 7 shows one form of locking wedge employed. Fig. 8 shows a modified form of the joint with the splice removed. Fig. 9 shows a perspective view of the complete modified form of joint. Fig. 10 shows a sectional end view of said modified form, and Fig. 11 shows another form of locking wedge.

Referring now more particularly to the

drawings, wherein like numerals of reference designate similar parts in each of the figures, the numerals 1 and 2 refer, respectively, to the rails connected by my improved form of joint and the numeral 3 refers to the splice employed in my preferred form. In forming the joint, the adjacent ends of the rails, each have a lengthwise section cut away, as shown in Fig. 3, said sections being cut away along the axial line of each rail from the free end back a suitable distance and then along a transverse line to the side of the rail. The splice 3, in general contour, is of a form to fit into the cut away space and supply the parts of the rail which have been removed. The inner side of the splice 3 has a longitudinal dove-tailed groove 4 and the adjacent sides of the rail ends have longitudinal dove-tailed ribs 5 and 6, which fit into the groove of said splice and lock the ends of the rail together. In the formation of the joints, the rail 1 may be moved endwise relative to the splice, the rib 5 sliding into the groove 4 until the end of the splice abuts against the shoulder 7 of said rail. The rib 6 of rail 2 should then be started into the opposite end of the groove 4 and said rail 2 inforced endwise until the ends of the rails 1 and 2 meet. The splice 3 is of sufficient length to abut against the shoulder 8 of rail 2 at the same time that the rail ends come together.

In order to lock the rails against separation, transverse dove-tail grooves 9 and 10 have been cut across the tread of the rails and splice, near the ends of said splice and wedges 11 are then driven transversely through said grooves and the ends of said wedges are then spread, as shown, so as to secure them in position.

The modified form of the device, as shown in Figs. 8, 9 and 10 is provided primarily for use in case a rail should become broken. If a rail should become broken, it would be impossible to substitute one and join it to the adjacent rails by means of joints, such as shown in Figs. 1 to 6 inclusive, so in the case of a broken rail, two rails are taken up from the track, one of which is the broken rail and these rails are replaced with two rails, the abutting ends of which have been made and constructed, as shown in Figs. 8 to 10 inclusive, and which will be described in detail hereinafter. The other ends of these two rails are formed in the manner shown in Figs. 1, 2, 3 and 4 and are joined

to the abutting rails in the manner hereinbefore described.

The construction of the modified form of joint is as follows: The outer sides of the webs at the abutting ends of the rails 12 and 13 are provided with dove-tailed ribs 14 and 15 in perfect alinement, and a splice 16 is provided whose inner side is of a contour to conform to and fit against the side of the rail end. This splice is of a length equal to the combined lengths of the ribs 14 and 15 and its inner side has a lengthwise dove-tailed groove 17. In forming this joint the abutting rail ends are brought together so as to bring the ribs 14 and 15 into alinement and the splice is then placed in position so as to bring its groove into alinement with said ribs. The splice is then moved lengthwise until the ribs are seated in said groove. In this form of joint transverse dove-tailed grooves 18 and 19 are also cut across the treads of the rails and splice, as is the case in the form shown in Figs. 1 and 2 and wedges 20 dove-tailed in cross section, are secured in said transverse grooves, the ends of said wedges being bent over and spread, as shown, so as to lock them against displacement.

The rail webs at the ends of the rail, in both forms of the joint, should be made somewhat thicker than the usual form of web, so as to allow material for the construction of the dove-tailed tongue, and the splice should be sufficiently heavy and contain sufficient material to permit of a strong dove-tailed groove therein.

The modified form of joint, as shown in Figs. 8, 9 and 10, while it will ordinarily be used in repairing track and in the replacement of broken rails, may also be used generally in track construction.

What I claim is:—

1. A device of the character described, consisting of two rails, whose ends abut, a dove-tailed rib integral with the side of each rail end, said ribs being in alinement, a splice whose inner side has a dove-tailed groove in which said ribs are seated, the tread of the abutting end of each rail having a transverse groove, said grooves extending also through said splice and wedges in said grooves for locking said splice and rails against relative lengthwise movement.

2. A device of the character described consisting of two rails whose ends abut together, a rib integral with the side of each rail and arranged in alinement, at said rail ends, a splice whose inner side is provided with a lengthwise groove, in which said ribs seat, the tread of the abutting end of each rail having a transverse groove, said grooves extending also through said splice and wedges

in said grooves for locking said rails to said splice so as to prevent their lengthwise movement relative thereof.

65

3. A device of the character described consisting of two alined rails, a rib carried by the adjacent end of each rail, said ribs being arranged in alinement, a splice whose inner side has a lengthwise groove in which said ribs seat, transverse dove-tailed grooves extending across said rails and splice and wedges, dove-tailed in cross section, in said transverse grooves which lock the rails against lengthwise movement relative to the splice.

4. A device of the character described consisting of two rails, whose ends abut, the abutting end of each rail having a lengthwise section cut away along the axial line of each rail, a splice in general contour of a form to fit into the cutaway space and supply the parts of a rail which have been removed, the inner side of said splice having a longitudinal dove-tailed groove, dove-tailed ribs integral with the sides of the rail ends adjacent said splice and fitting into said groove and locking said splice to said rail ends, said rails and splice having transverse grooves across their tread and locking wedges in said grooves.

85

5. A device of the character described consisting of two rails whose ends abut, a rib carried by the end of each rail and integral with the web thereof, said ribs being arranged in alinement, a splice whose inner side is of a contour to conform to the sides of said rails, said splice being provided with a lengthwise groove along its inner side in which said ribs seat, the tread of said rails and splice having transverse grooves and wedges in said grooves for locking said rails and splice against lengthwise movement relative to each other.

95

6. A device of the character described consisting of two rails whose ends abut, a dove-tailed rib integral with the web of each rail end, said ribs being in alinement, a splice whose inner side is of a contour to conform with the sides of said rails, said splice being provided with a lengthwise groove along its inner side, in which said ribs seat, transverse dove-tailed grooves extending across said rails and splice, and wedges dove-tailed in cross section in said transverse grooves which lock the rails against lengthwise movement relative to the splice.
